US00D787688S

(12) **United States Design Patent** (10) **Patent No.:** **US D787,688 S**
(45) **Date of Patent:** **** May 23, 2017**

(54) **WOUND DRESSING**

(71) Applicant: **Crawford Woundcare Limited,**
Knutsford (GB)

(72) Inventor: **Christian Stephenson**, Wilmslow (GB)

(73) Assignee: **Crawford Woundcare Limited,**
Knutsford (GB)

(**) Term: **14 Years**

(21) Appl. No.: **29/496,147**

(22) Filed: **Jul. 9, 2014**

(51) LOC (10) Cl. **24-04**

(52) U.S. Cl.

USPC **D24/189**

(57) **CLAIM**

The ornamental design for a wound dressing, as shown and described.

DESCRIPTION

FIG. 1 is a front view of a first embodiment of a wound dressing showing the new design;

FIG. 2 is a back view thereof;

FIG. 3 is a right view thereof;

FIG. 4 is a left view thereof;

FIG. 5 is a top view thereof;

FIG. 6 is a bottom view thereof; and

FIG. 7 is a perspective view thereof.

The broken lines immediately adjacent to the shaded areas, represent the bounds of the claimed design while all other broken lines are directed to environment and are for illustrative purposes only; the broken lines form no part of the claimed design.

1 Claim, 4 Drawing Sheets
